UNITED STATES PATENT OFFICE.

WILLIAM F. BECHTEL, OF LEHIGH, IOWA.

MAIL-BAG CATCHER.

Application filed November 15, 1921. Serial No. 515,302.

To all whom it may concern:

Be it known that WILLIAM F. BECHTEL, a citizen of the United States of America, residing at Lehigh, in the county of Webster 5 and State of Iowa, has invented new and useful Improvements in Mail-Bag Catchers, of which the following is a specification.

The object of the invention is to provide simple and efficient means for use in connection with railway mail trains for catching and collecting the mail while the train is in motion to avoid the stopping or reduction of the speed thereof at mail stations, and more particularly to provide a device of 10 this type which is adapted upon receipt of the mail sack or package to immediately discharge the same into the mail car to avoid the possibility of dropping the same and obviate the necessity of the attendant reaching 15 out beyond the plane of the side of the car to remove the sack from the catching means; and with these objects in view the invention consists in a construction and combination of parts of which a preferred embodiment 20 is shown in the accompanying drawings, wherein:—

Figure 1 is a side view of a mail catching apparatus embodying the invention, showing the same from the inner side of the car 25 and arranged in position for operation.

Figure 2 is a plan view of the same.

Figure 3 is a front view of the mail receptacle.

Figure 4 is a horizontal sectional view of 30 the mail receptacle.

Figure 5 is a detail view of the cushioning pad carried by the receptacle in the path of mail sacks or packages received thereby.

The apparatus consists essentially of a 40 swinging receptacle 10 mounted for pivotal movement in a horizontal plane upon an upright spindle 11 and provided with a grip or handle 12 by which it may be moved to the operative position indicated in Figures 45 1 and 2.

Extending inwardly from the receptacle is an arm 13 to which is pivotally connected a link 14, and with the free end of this link are connected opposed tensile springs 15 and 50 16. There is a stop 17 on the arm 13 arranged in the path of the link and serving to prevent the latter from swinging movement rearwardly beyond a position in the plane of the arm 13, and the effect of the 55 opposed tensions of the springs 15 and 16 when the receptacle is in the operative posi-

tion indicated in Figures 1 and 2, is to swing the receptacle to the inoperative or mail discharging position with the open front of the receptacle directed inwardly toward the car. 60 To hold the receptacle in the mail receiving position as indicated in Figures 1 and 2, in opposition to the tension of the spring 15, there is employed a retaining hook 18 pivoted at 19 for downward swinging movement from its engaging position and engaged with a keeper or eye 20 on the receptacle. The tendency of this hook to swing in the direction indicated by the arrow in Figure 1 and thereby become disengaged 70 from the eye 20 and release the receptacle for folding movement under the stress of the spring 15, may as illustrated be supplemented by a spring 21, but when the hook is arranged in engagement with the 75 eye 20 to which position it may be moved by means of an operating cord 22 designed for manipulation by the operator or mail clerk, it is held in such position by the strain on the hook due to the tendency of the receptacle to be returned to its normal position 80 by the spring 15. Any severe jar applied to the receptacle or more especially to the outer end or projecting portion of the receptacle in a rearward direction as shown 85 by the arrow adjacent thereto, and for example such a jar as that which is applied by a mail sack or package forcibly entering the receptacle or caught by the receptacle while the car is in forward motion, will tend to 90 move the receptacle slightly in the direction indicated by said arrow adjacent thereto and thereby relieve the hook of the strain applied thereto by the eye 20, which will release the hook and allow it to be disengaged from the eye so that the spring 15 may then swing the receptacle to the position to 95 discharge the mail sack or other package into the car.

The connection of the operating spring 15 with the receptacle is effected through the agency of the link 14 and the opposing spring 16 in order that there may be an opportunity for a rearward movement of the outer or exposed end of the receptacle 10 to 105 permit of its release from the hook and hence the return of the receptacle to the interior of the car.

As above indicated the grip or handle 12 is designed to facilitate the movement of the 110 receptacle to its receiving or exposed position, and when so swung it is only necessary

for the operator, using the other hand for that purpose to draw upon the cord 22 to raise the hook into a position to engage the eye and thereby lock the receptacle in the receiving position.

Arranged within the receptacle in the path of objects projecting thereinto or caught thereby is a cushioning pad 23 shown in detail in Figure 5 and secured in place by terminal hooks 24 in contact with a seat consisting of a series of transversely disposed coiled springs 25 spanning an opening 26 in the rear wall of the receptacle. Obviously said cushion or pad is designed to cushion the blow of the mail sack or other package against the receptacle to avoid injury to either.

Having described the invention, what is claimed as new and useful is:—

1. A mail catching apparatus having a receptacle mounted for swinging movement in a horizontal plane to project an end thereof beyond the vertical plane of the side of a car, a return spring connected with the inner end of the receptacle for swinging the latter to its normal position within the car, and means, releasable by a jar applied rearwardly to the exposed end of the receptacle for holding the latter in its mail receiving

position in opposition to said return spring, the receptacle being provided with a grip or handle for swinging the same to its receiving position, and an operating cord being connected with said locking means for moving the latter to the receptacle engaging position.

2. A mail catching apparatus having a receptacle mounted for swinging movement in a horizontal plane to project an end thereof beyond the vertical plane of the side of a car, a return spring connected with the inner end of the receptacle for swinging the latter to its normal position within the car, and means, releasable by a jar applied rearwardly to the exposed end of the receptacle for holding the latter in its mail receiving position in opposition to said return spring, the connection between the receptacle and the return spring having a link pivotally mounted upon the receptacle for swinging movement in the plane thereof and having said return spring connected with the free end thereof, and a second spring connected with said link in opposing relation with the return spring.

In testimony whereof he affixes his signature.

WILLIAM F. BECHTEL.
